United States Patent Office

Des. 206,395
Patented Dec. 6, 1966

206,395

OUTDOOR LIGHT POST

Donald Deskey, 222 Central Park S., New York, N.Y.
10019, and Alexander Lurkis, 193—12 Nero Ave., Hol-
liswood, N.Y. 11423

Filed July 13, 1965, Ser. No. 86,140

Term of patent 14 years

(Cl. D48—31)

FIGURE 1 is a side elevational view of an outdoor light post, showing our new design;

FIGURE 2 is a top plan view thereof;

FIGURE 3 is a top plan view thereof, the post being rotated 90°;

FIGURE 4 is a side elevational view corresponding to FIGURE 2; and

FIGURE 5 is a side elevational view corresponding to FIGURE 3.

The broken line showing of a luminaire and a base in FIGURE 1 is for illustrative purposes only. FIGURES 4 and 5 are shown broken away to indicate indeterminate length.

We claim:

The ornamental design for an outdoor light post, as shown and described.
